(57) **CLAIM**

The ornamental design for a kit bag, as shown and described.

DESCRIPTION

FIG. 1 is a front isometric view of a kit bag.

FIG. 2 is a front elevation view of the kit bag of FIG. 1.

FIG. 3 is a rear elevation view of the kit bag of FIG. 1.

FIG. 4 is a left side elevation view of the kit bag of FIG. 1. FIG. 5 is a right side elevation view of the kit bag of FIG. 1.

FIG. 6 is a top plan view of the kit bag of FIG. 1; and, FIG. 7 is a bottom plan view of the kit bag FIG. 1. The broken lines depict portions of the article that form no part of the claimed design.
